UNITED STATES PATENT OFFICE.

ERNEST H. SCHMIDT, OF CLEVELAND, OHIO, ASSIGNOR TO THE NATIONAL MALLEABLE CASTINGS COMPANY, OF CLEVELAND, OHIO, A CORPORATION OF OHIO.

COUPLING-YOKE.

1,279,015.

Specification of Letters Patent. Patented Sept. 17, 1918.

Application filed June 6, 1914. Serial No. 843,412.

To all whom it may concern:

Be it known that I, ERNEST H. SCHMIDT, a citizen of the United States, residing at Cleveland, Cuyahoga county, Ohio, have invented new and useful Improvements in Coupling-Yokes, of which the following is a specification, reference being had to the accompanying drawings, in which—

Figure 1 is a plan of my improved yoke, partly in section, applied to the underframing of a car; Fig. 2 is a side elevation thereof, partly in section; Fig. 3 is a front elevation thereof; Fig. 4 is a detail of the filler block; Fig. 5 is a front elevation of a modification of my invention, and Fig. 6 is a detail of the filler block used with such a modified structure; Fig. 7 is a front elevation of a further modification, and Fig. 8 is a detail of the filler block used therewith. My invention relates to improvements in coupler yokes designed to receive in the forward end thereof the butt end of a car coupler, and provides a strong, simple and convenient form of yoke to which the coupler can be readily connected or disconnected without necessitating removal of the yoke or draft rigging from the car, or the draft rigging and yoke may be taken down without removing the coupler. My invention also consists in the construction and co-operation of the parts which I shall herein-after describe and claim.

Referring to the drawings, the numeral 2 represents the shank of an automatic coupler of any approved type, which terminates in a butt or liner block 3. The yoke, which is preferably of cast steel, comprises two parts, the main body portion 4 consisting of the usual upper and lower arms 5 and 6 connected at their rear ends by a vertical portion 7, and a filler block 8 to be hereinafter described. Upon the exterior faces of the yoke 4 is a strengthening rib 9, which is reinforced at the rear end of the yoke by the flanges 10. The forward end of the arm 5 terminates at the rear of the coupler liner block 3, while the forward end of the upper arm 6 extends over and engages by its abutment 11 the forward face 12 of the coupler liner block 3. Formed integrally with the forward end of the arm 6 are vertically extending side walls 13, the lower rear faces of which are made integral with the forward end of the lower arm 5. The forward end of the arm 6 and the side walls 13 form

a housing which incloses the top and sides of the liner block 3. The side walls 13 preferably flare forwardly and outwardly, to permit a limited lateral angling of the coupler relative to the yoke, and thereby relieve the side walls and the yoke of side strains.

The side walls 13 are adapted to receive between their lower extremities the filler block 8, and have recesses 14, in which the laterally projecting lugs 15 on the filler block are adapted to enter and which act as a support to the filler block. The filler block 8 has also a downwardly extending web 16, reinforcing hookshaped flanges 17, which take about the downward extensions 18 of the side walls 13, and thereby form an interlocking engagement between these parts to prevent spreading and inward collapsing of the side walls 13, such as may occur under heavy stresses. Upon the upper face of the filler block is an abutment 19, which is adapted to engage the forward face 12 of the coupler liner block and to have a pulling engagement therewith. The filler block has also a rear wall 20, which abuts against the forward end of the lower arm 5, and a lip 21, which underlies the lower arm 5 to prevent the rear end of the filler from tilting upwardly when a heavy pulling stress is applied to the abutment 19 by the coupler liner block.

The pulling stresses transmitted from the coupler liner block to the filler block are taken up by the key member 22, and by it transmitted to the side walls 13 of the yoke. The key member 22 is seated in registering apertures 23 and 24 in the side walls 13 and filler block 8 respectively.

The connection between the yoke and the coupler is made as follows:

After the yoke is placed in position between the draft sills 25 of the car the liner block 3 of the coupler is inserted from below between the side walls 13, and is then raised so that its front upper edge 12 engages the abutment 11 of the upper yoke arm 6. The filler block 8 is then inserted from the forward side with its laterally-projecting lugs 15 seated in recesses 14 in the side walls 13, and with its upper face 26 engaging the bottom of the coupler liner block 3 and with its abutment 19 engaging the forward face 12. When the filler block has been slid longitudinally into such a position, with its lip 21 underlying the forward

end of the lower yoke arm 5, the key 22 is inserted transversely through the registering apertures 23 and 24 of the side walls 13 and filler block 8 respectively. The key may be held in position by any suitable means, such as the cotter pins 27. The side walls of the yoke are open to the rear, and the coupler is prevented from moving farther rearwardly by the usual front follower 28 of the draft rigging, which is inclosed within the yoke.

It will be seen that when the parts are assembled as described, the yoke has a pulling engagement with the liner block of the coupler at the top through the abutment 11 of the upper arm 6, and at the bottom through the abutment 19 of the filler block 8, which in turn is held in position by the key 22 engaging the side walls 13, so that no securing means for the coupler liner block, other than the key 22, is required.

My invention is of great advantage since it enables the coupler to be secured to or disengaged from the yoke, either by a horizontal or vertical movement, and without the removal of the yoke and draft rigging from the car, for the reason that the positions of the filler block 8 and key 22 may be so low with relation to the plane of the draft sills 25 of the car that the key can be inserted without interference from the draft sills, as is best shown in Fig. 3. At most, a slight recessing of the undersides of the draft sills 25 will provide easy entrance or removal of the key 22, thereby enabling the ready disengagement or engagement of the coupler and the yoke without taking down the latter from its position on the car.

It will also be seen that the engagement of the filler block 8 with the yoke is such that the side walls 13 are prevented from spreading or collapsing; that the filler 8 is horizontally and longitudinally slidable into engagement with the side walls 13 and acts as a support for the coupler liner block 3; that the rear end of the filler block 8 is prevented from tipping upwardly by the lip 21 under pulling stresses; that the filler block transmits pulling stresses from the coupler to the key 22 and thence to the side walls 13, and that the key is removable laterally beneath the draft sills without necessitating cutting them away for this purpose.

In Figs. 5 and 6 I have shown a modified form of my device, in which the recesses 14' 55 coöperate with the projections 15' on the filler block 8' to form not only a support for the filler block but also to prevent spreading or collapsing of the side walls 13' through the engagement of the lips 29 on 60 the projections 15' with the depending lugs 30 of the side walls 13'.

In Figs. 7 and 8 I have shown a further modification, which constitutes a reversal of the construction I have illustrated in Figs. 65 5 and 6, the projections 15² on the filler block 8² having downwardly-extending lugs 31, which lugs engage inner faces 32 of the recesses 14² and thereby not only support the filler block in its position in the yoke 70 but prevent the side walls 13² from spreading or collapsing.

It is obvious that various modifications may be made in the constructions which I have shown and described without departing 75 from my invention.

What I claim is:

1. A coupler yoke comprising two forwardly extending arms, side walls connected to said arms, a filler block having an engagement with the side walls against vertical movement and having a rearwardly extending lip engaging one of the yoke arms, to prevent tipping, the said yoke and filler block having bearings for the coupler liner 80 block, and a key member adapted to transmit pulling stresses from the filler block to the yoke.

2. A coupler yoke comprising upper and lower arms, side walls extending upwardly 90 from said lower arm to said upper arm and forming a housing inclosing the top and sides of the coupler butt, a removable member seating between said side walls beneath said coupler butt and in pulling engagement 95 therewith, said removable member having laterally-projecting lugs seating in lateral recesses in the housing and having also an interlocking engagement with the walls of the housing to prevent spreading or collapsing 100 of said walls.

ERNEST H. SCHMIDT.
